S. JASGUR.
GARMENT FASTENER.
APPLICATION FILED JUNE 4, 1920.

Patented Feb. 22, 1921.

Inventor

Samuel Jagger

By his Attorney

Horace Freeman

UNITED STATES PATENT OFFICE.

SAMUEL JASGUR, OF NEW YORK, N. Y.

GARMENT-FASTENER.

1,369,437.

Specification of Letters Patent. Patented Feb. 22, 1921.

Application filed June 4, 1920. Serial No. 386,450.

To all whom it may concern:

Be it known that I, SAMUEL JASGUR, a citizen of the United States, residing in the city of New York, county of Bronx, borough of Bronx and State of New York, have invented certain new and useful Improvements in Garment-Fasteners, of which the following is a full, clear, and exact specification.

10 My invention relates to garment fasteners and refers particularly to fasteners suitable for use upon trousers.

Many devices have been devised for holding together the two sides of the frontal opening of trousers at the waist band, where the strain upon the fastener is considerable.

In order to meet the requirements of a fastener of this character, it must be cheap, simple in construction, readily and firmly 20 attached to the fabric, must not have a tendency to tear the fabric and must be capable of ease of operation in coupling and uncoupling.

There are two general groups of such 25 fasteners, those which are sewed to the fabric and those having extended projections capable of passage through the fabric and then turned over to prevent their withdrawal from the fabric.

30 Sewed fasteners are objectionable as they soon become loosened from the fabric and those fasteners which are attached to the fabric by means of ordinary tongues, or projections, tear the fabric under strain and 35 become loosened therefrom.

The device of my invention overcomes all of these objectionable features and presents all of the advantages mentioned above.

In the accompanying drawings, representing one form of the device of my invention, similar parts are designated by similar numerals.

Figure 1 is an elevation of one form of 45 my device as applied to the upper portion of a pair of trousers.

Fig. 2 is a section through the line 2—2 of Fig. 1.

Fig. 3 is a section through the line 3—3 of Fig. 1.

50 Fig. 4 is a development of the device shown in Fig. 1.

Fig. 5 is a view of Fig. 4 in the direction of the arrow 5.

The particular form of my device, illustrated in the accompanying drawings, com-

prises a sheet, or blank, of flexible material, as metal, composed of the two integral members 10 and 11 capable of being folded along the line A—A, in order that the two members 10 and 11 may be superimposed one above the other. 60 The member 10 has the approximately circular opening 12 extended into the elongated opening 13, and the member 11 has the approximately circular opening 14 extended into the elongated opening 15, the openings 65 in the members 10 and 11 being so situated with respect to each other that they will be in alinement when the device is folded along the line A—A.

The member 10 has the recesses 16, 17 and 70 18 into which the tongues 19, 20 and 21 of the member 11 may be respectively inserted when the members 10 and 11 are in superimposed position, the tongues being capable of being folded over the member 10, when thus 75 inserted, and acting as a locking means.

The member 10 has an extended flange 22 around the openings 12, 13, corresponding to the shape thereof, the outer edge of which practically abuts upon the inner surface of 80 the member 11, when the members 10 and 11 are in parallel positions with respect to each other.

The application of my device to fabrics and, especially, as a closing means for the 85 frontal opening of trousers is as follows:

The device, with the tongues 19, 20 and 21 in a practically right angled position with respect to the plane of the member 11, is partially folded upon the line A—A, the 90 fabric 23 having an opening therein corresponding to the openings 12, 13 and 14, 15 is inserted and the two members 10 and 11 brought into practically parallel position with respect to each other, at the same time 95 the tongues 19, 20 and 21 penetrating the fabric 23 and parting through the recesses 16, 17 and 18. The three tongues 19, 20 and 21 are then bent over thus locking together the two members 10 and 11. 100

The flange 22 of the member 10 thus abuts upon the member 11, forming a button hole with metallic sides and edges.

The button 24, fixedly attached to the fabric 25, may be inserted through the openings 105 12 and 14 and the opening in the fabric 25 and will be drawn into the openings 13 and 15, the widths of which are less than the diameter of the button 24.

It is to be noted that the folded ends of 110

the tongues 19, 20 and 21 abut upon the metallic member 10 and thus can not be pulled out of the fabric.

It will be seen from the above that my device may be readily and firmly attached to a fabric and that the button, or other similar means, does not pull directly upon the fabric and that a practically complete metallic button hole, or fastening means, is thus formed.

I prefer to use the means described for fastening my device to the fabric, but any other suitable means may be employed.

I do not limit myself to the particular size, shape, number and arrangement of parts as shown and described, all of which may be varied without going beyond the scope of my invention as shown, described and claimed.

20. What I claim is:—

1. In a fabric fastening device, in combination, a foldable blank, a plurality of openings within the blank capable of being placed in alinement with each other when the blank is folded and a plurality of tongues carried by the blank capable of being extended beyond and folded over the folded blank.
2. In a fabric fastening device, in combination, a foldable blank, a plurality of openings within the blank capable of being placed in alinement with each other

when the blank is folded, a flange surrounding one opening capable of practical abutment upon the folded blank and a plurality of tongues carried by the blank capable of being extended beyond and folded over the folded blank.

3. In a fabric fastening device, in combination, a foldable blank, a plurality of openings within the blank capable of being placed in alinement with each other when the blank is folded, a plurality of recesses in one portion of the blank and a plurality of tongues in the other portion of the blank capable of being extended through the recesses and folded over the first portion of the folded blank.

4. In a fabric fastening device, in combination, a foldable blank, a plurality of openings within the blank capable of being placed in alinement with each other when the blank is folded, a flange surrounding one opening capable of practical abutment upon the folded blank, a plurality of recesses in one portion of the blank and a plurality of tongues in the other portion of the blank capable of being extended through the recesses and folded over the first portion of the folded blank.

Signed at New York city in the county of New York and State of New York this 28 day of May, 1920.

SAMUEL JASGUR.
